UNITED STATES PATENT OFFICE.

ALFRED MOTZER, OF MERIDEN, CONNECTICUT, ASSIGNOR TO THE HOBSON & MOTZER CO., OF MERIDEN, CONNECTICUT, A FIRM COMPOSED OF HARRY C. HOBSON AND ALFRED MOTZER.

AUXILIARY OILING SYSTEM FOR FORD CARS.

1,328,388.

Specification of Letters Patent. Patented Jan. 20, 1920.

Application filed May 13, 1919. Serial No. 296,875.

To all whom it may concern:

Be it known that I, ALFRED MOTZER, a citizen of the United States, residing at Meriden, in the county of New Haven and State 5 of Connecticut, have invented a new and useful Improvement in Auxiliary Oiling Systems for Ford Cars; and I do hereby declare the following, when taken in connection with the accompanying drawings and the 10 characters of reference marked thereon, to be a full, clear, and exact description of the same, and which said drawings constitute part of this application, and represent, in—

Figure 1 a view partly in elevation and 15 partly in vertical section of my improved auxiliary oiling system for Ford cars.

Fig. 2 an end view thereof, with straps removed.

Fig. 3 a broken sectional view of the valve 20 on the line 3—3 of Fig. 2, showing the two-way valve in its open position.

Fig. 4 a corresponding view showing the valve in its closed position.

Fig. 5 a broken sectional view of the valve 25 on the line 5—5 of Fig. 1 showing the valve in its open position.

My invention relates to an improved auxiliary oiling system particularly adapted for Ford cars, the object being to provide simple and convenient means for carrying reserve oil without raising the oil level in the 30 engine.

With these ends in view, my invention consists in an auxiliary oiling system, having certain details of construction as will be hereinafter described and pointed out in the 35 claim.

In carrying out my invention, I employ a reservoir 6 having a filling nipple 7 and 40 vented cap 8, the reservoir being adapted to receive an amount of oil far in excess of the oil receptacles of Ford cars. Straps 9 embracing the ends of the reservoir are provided for securing the same in place. Upon 45 the under side of the reservoir I locate a separate feed-chamber 10 in one side of which I mount a glass 11 through which the oil in the chamber may be seen, the feed-chamber being of much less capacity than 50 the reservoir and adapted to contain say a pint or a quart of oil or other unit of measurement. Depending from the feed-chamber is a valve-casing 12 connected by a lead pipe 13 with the bottom of the reservoir.

The said casing receives an ordinary two-way valve 14 provided at its projecting outer end with an operating handle 15 and having its projecting inner end encircled by a spring 16 by means of which it is constantly maintained upon its seat in the ordinary manner. 55 The said valve is formed with a radial passage 17 and a corresponding radial passage 18 located at a right angle thereto as clearly shown in Figs. 3 and 4. A port 19 leads from the bottom of the chamber 10 through 60 the valve-casing, while a corresponding port 20 located at a right angle to the port 19, is formed in the casing and connected with a feed-pipe 21 which leads to the so called "breather pipe" of the engine. 70

When the valve is in its open position, as shown in Fig. 3, oil in the reservoir feeds by gravity through the lead pipe 13 and through the passages 17, 18 and 19 into the feed-chamber 10 which is in this way filled by 75 gravity. When the chamber has been filled in this manner, the handle 15 is thrown into its closed position as shown in Fig. 4 by broken lines, whereby all communication between the reservoir and chamber is shut off, 80 and whereby the passages 19, 17, 18 and 20 are connected to permit the oil in the chamber to feed into the feed-pipe 21. In this manner the oil in the reservoir is fractionally, so to speak, transferred therefrom into 85 the feed chamber from which it is fed to the engine without, however, drawing on the main body of oil in the reservoir during the feeding operation. When the oil in the chamber has been fed therefrom to the engine, 90 the handle 15 is thrown into its open position and allowed to remain there until the chamber has been refilled from the reservoir. The handle is left in its open position, until it becomes necessary to feed more oil 95 into the engine when the handle is thrown into its closed position to empty the feed chamber into the engine.

I claim:—

In a gravity auxiliary oiling system for 100 Ford cars, the combination with a reservoir, of mounting means therefor, of a feed-chamber suspended from the said reservoir and of smaller capacity than the same, an oil-level indicator mounted in the said feed-chamber 105 for indicating the amount of oil therein at any given time, a valve-casing suspended from the said feed-chamber, a lead-pipe

from the reservoir to the said valve-casing, a feed-pipe leading from the said casing to the engine, and a two-way valve mounted in the said casing and provided with passages, whereby in its open position the valve permits the feed-chamber to be filled by gravity from the reservoir and in its closed position shuts the chamber off from the reservoir and permits the oil in the chamber to be fed by

gravity into the feed-pipe and thence into the engine.

In testimony whereof, I have signed this specification in the presence of two subscribing witnesses.

ALFRED MOTZER.
